EXPANSIBLE COAT HANGER

Arthur D. Baker, San Fernando, Calif.

Application May 22, 1953, Serial No. 356,663

2 Claims. (Cl. 223—94)

1

This invention relates to expandable coat hangers and more particularly to a coat hanger the length of which can be varied to accommodate the hanger to garments of different sizes.

It is among the objects of the invention to provide an improved coat hanger which can be adjustably elongated and contracted to accommodate the hanger to garments of various sizes; which is frictionally held in its various positions of adjustment and utilizes the weight of garments supported thereon to resist change from selected positions of adjustment; which is of sufficient thickness to avoid creasing or wrinkling garments supported thereon; and which is simple and durable in construction, economical to manufacture, easy to use, and neat and attractive in appearance.

Other objects and advantages will become apparent from a consideration of the following description and the appended claims in conjunction with the accompanying drawing, wherein:

Figure 1 is a side elevational view of a coat hanger illustrative of the invention with portions broken away and shown in cross section to better illustrate the construction thereof;

Figure 2 is a cross sectional view on the line 2—2 of Figure 1; and

Figure 3 is a cross sectional view on the line 3—3 of Figure 1.

With continued reference to the drawing, the coat hanger comprises a symmetrically bowed shoulder bar, generally indicated at 10, including constituent portions 11 and 12 in the form of longitudinally curved bars pivotally interconnected at adjoining ends for angular movement relative to each other about an axis substantially perpendicular to a plane including the longitudinal center lines of both of the bars 11 and 12. The bar 11 has at its end adjacent the bar 12 an offset 13 projecting outwardly of the convex side of the shoulder bar and provided at its distal end with an apertured tongue formation 14 of reduced thickness and the bar 12 has at its end adjacent the bar 11 an offset portion 15 projecting outwardly of the convex side of the shoulder bar and provided at its distal end and at the side thereof adjacent the offset formation 13 of the bar 11 with a pair of spaced apart, apertured ears 17 and 18 between which the tongue formation 14 is disposed. A pivot pin 19 extends through the registering apertures in the ears 17 and 18 and the tongue 14 to pivotally interconnect the bars 11 and 12 together for angular movement relative to each other.

Near its end remote from the bar 12 and at

5 the inner or concave side thereof the bar 11 is provided with spaced apart, apertured ear formations 20 and 21 and a rod 22 has one end disposed between these ear formations. A pivot pin 23 extends through registering apertures in the ears 20 and 21 and in the end portion of the rod 22 received between these ears and pivotally connects the rod 22 at one end to the bar 11 at the corresponding end of the shoulder bar 10.

10 The bar 12 is provided near its end remote from the bar 11 and at the inner or concave side thereof with a pair of spaced apart, apertured ear formations 24 and 25 and a rod 26 has one end thereof disposed between these ear formations and pivotally connected thereto by a pivot pin 27 extending through registering apertures in the ears 24 and 25 and in the end portion of the rod 26 disposed between these ear formations. A tube 28 is disposed between the ends of the shoulder bar 10 of the hanger and slidably receives the rods 22 and 26, these rods having a sufficient frictional engagement with the tube 28 to tend to hold the bar portions 11 and 12 of the shoulder bar 10 in selected positions of 15 angular adjustment relative to each other.

20 A stem 30 constituted by a length of heavy wire extends transversely through the shoulder bar 10 at the adjacent ends of the constituent bars 11 and 12 of the shoulder bar and has on one end an eye formation 31 which receives the tube 28 intermediate the length of this tube. A hook formation 32 is provided on the other end of the stem and is disposed outwardly of the side of the shoulder bar 10 remote from the tube 28 and spaced from the distal ends of the offsets 13 and 15 of the bars 11 and 12.

25 The end of the bar 12 adjacent the bar 11 is provided with a notch 33 which extends longitudinally of the corresponding end of the bar 12 and through which the stem 30 extends to provide freedom of angular movement of the bar 12 relative to the bar 11 without interference by the stem.

30 The stem 30 is freely slidable through the shoulder bar 10 and, when the hanger is suspended by the hook 32 and supports a garment thereon, the stem 30 pulls upwardly on the intermediate portion of the tube 28 applying a bending force to the assembly including the tube 28 and the rods 22 and 26 which releasably locks the bars 11 and 12 in selected position of angular adjustment relative to each other.

35 The invention may be embodied in other specific forms without departing from the spirit or essential characteristics thereof. The present

embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. An expandible coat hanger comprising a pair of longitudinally curved bars pivotally interconnected at adjoining ends for relative angular movement about an axis perpendicular to a plane including the longitudinal center lines of both of said bars and together constituting a bowed shoulder bar of the hanger, rods pivotally secured each at one end to said shoulder bar one at each end of the latter and extending toward each other from the corresponding ends of the shoulder bar, a tube disposed between the ends of said shoulder bar and slidably receiving said rods, and a stem extending through said shoulder bar adjacent the pivotal connection between the constituent portions thereof and having on one end an eye formation receiving said tube and on its other end a hook formation spaced from the edge of said shoulder bar remote from said tube, said shoulder bar being expandible and contractible by relative angular movement of the constituent portions thereof about the pivotal connection therebetween and said stem being effective when subjected to the weight of a garment on said hanger to apply a bending

10

25

force to the tube and rod assembly and thereby releasably lock the constituent portions of said shoulder bar in selected positions of angular adjustment relative to each other.

2. An expandible coat hanger comprising a bowed shoulder bar including a pair of constituent portions of substantially equal length pivotally interconnected at adjoining ends for relative angular movement about an axis disposed substantially perpendicular to a plane including the longitudinal center line of said shoulder bar, an assembly connected between the ends of said shoulder bar including an intermediate member and end members pivotally connected one to each end of said shoulder bar and slidably engaged with said intermediate member to frictionally hold the constituent portions of said shoulder bar in selected positions of angular adjustment relative to each other, and a stem extending slidably through said shoulder bar adjacent the pivotal connection between said constituent portions thereof and connected at one end to the intermediate member of said assembly intermediate the length of the latter and having a hook formation on its other end.
